GARMENT

Harry A. Cornblum, Cleveland, Ohio

Application May 22, 1933, Serial No. 672,101

4 Claims. (Cl. 2—106)

This invention relates as indicated to garments, but has reference more particularly to sport garments of the coat or jacket type, such, for example, as "windbreakers".

5 A primary object of the invention is to provide a garment of this type which may be worn either in the "Cossack" style, i. e., with the bottom in unshirred or ungathered condition, or with the bottom shirred or gathered into snug engagement 10 with the waist of the wearer. Another object of the invention is to provide a garment of the type described which has incorporated in the bottom thereof means manipulable or adjustable by the wearer to effect a gathering or shirring of 15 such bottom so as to provide a snug engagement thereof with the waist of the wearer.

To the accomplishment of the foregoing and related ends, said invention, then, consists of the means hereinafter fully described and particularly pointed out in the claims.

20 For the purpose of illustrating my invention I refer to the following description and accompanying drawing of a preferred form of the invention, although, it will be understood that the same 25 inventive principles may be applied in other ways.

In said annexed drawing:

Fig. 1 is a view showing the jacket worn with the bottom in unshirred condition; Fig. 2 is a view showing the jacket worn with the bottom in 30 shirred condition; Fig. 3 is a cross sectional view through the bottom of the jacket as shown in Fig. 1; Fig. 4 is a cross sectional view through the bottom of the jacket as shown in Fig. 2; Fig. 5 is a fragmentary perspective view of the inside 35 of the lower rear portion of the jacket; Fig. 6 is a fragmentary perspective view showing the manner in which the elastic web shirring members are secured together when the bottom of the jacket is in ungathered condition; and Fig. 40 7 is a fragmentary perspective view showing the manner in which the elastic web shirring members are secured together to effect the gathering 45 of the bottom of the jacket.

45 Referring more particularly to the drawing, it will be seen that the jacket 1 is provided with a hookless fastener 2 and has formed at the bottom thereof an inturned hem 3, which, except at a cutaway portion 4 thereof, is stitched to the body of the jacket so as to form a pocket 5.

Disposed within the pocket 5 are members 6 and 7 each of which is made of elastic webbing and has one end thereof secured to the jacket adjacent the hookless fastener 2 as by means of 55 a line of stitches 8. By securing the members 6

and 7 to the jacket in this manner they may, when worn out, be easily replaced.

When in unstretched condition, the members 6 and 7 terminate at the cutaway portion 4 of the hem 3, being secured to each other at this point as by means of a snap fastener, the male portion 9 of which is secured to the end of member 6 and the female portion 10 of which is secured to the end of member 7. The member 6 is also provided with the male portion 12 of a snap fastener, which is spaced from the fastener portion 9 and the member 7 is also provided with the female portion 11 of a snap fastener which is spaced from the fastener portion 10 the same distance as the fastener portion 12 is spaced from the fastener portion 9. 15

When the jacket is to be worn in the so-called "Cossack" style, i. e., with the bottom in unshirred condition, the male portion 9 of the snap fastener is secured to the female portion 10 thereof, and when thus secured to each other, the members 6 and 7 are in unstretched condition. When it is desired to draw the bottom of the jacket into snug engagement with the waist of the wearer, the elastic members 6 and 7 are 25 stretched sufficiently to permit the fastener portion 10 to be secured to the fastener portion 12 and fastener portion 11 to fastener portion 9, access to the members for this purpose being readily had by pulling the ends thereof through the opening 4 in the hem. This has the effect of 30 shirring the bottom of the jacket as illustrated in Figs. 2 and 4.

By providing for the relief of the strain in members 6 and 7 when the jacket is not worn or when worn with the bottom in unshirred condition, the life of these members is materially increased. By securing these members to the jacket in the manner hereinbefore described, instead of incorporating an elastic band as an integral part of the jacket bottom as is customary in jackets of this type, they may, when worn out, be easily replaced at a very low cost. The cost moreover, is considerably less than that of a knitted bottom, which is provided in some jackets 40 of this character. 45

Although the invention has been described particularly with reference to sport jackets and the like, it will be readily understood that it may be used in connection with various other types of 50 garments.

Other forms may be employed embodying the features of my invention instead of the one here explained, change being made in the form or construction, provided the elements stated by 55

any of the following claims or the equivalent of such stated elements be employed.

I therefore particularly point out and distinctly claim as my invention:

- 5 1. In a garment of the character described having a hem formed at the bottom thereof, elastic members disposed within said hem and removably secured to the garment, and means whereby said members may be secured to each 10 other in stretched or unstretched condition, so as to effect at will a shirred or unshirred condition of said bottom, said means comprising fastener elements arranged in pairs on each of said elastic members, with one of said elements 15 in each pair located at the extreme ends of said elastic members.
- 20 2. In a garment of the character described having a hem formed adjacent the bottom thereof, a pair of elastic web members disposed within said hem and having one end thereof secured to said garment and provided at their other ends with a plurality of fastener elements whereby said members may be secured together in a plurality of overlapping relations, each of said other ends of said elastic members having one 25 of said fastener elements located at its extreme end.
- 25 3. In a garment of the character described, a pair of elastic web members disposed in a hem adjacent the waistline of said garment and each secured at one of its ends to said garment ad-

jacent the front portion thereof, and means for fastening the other ends of said web members together so as to permit the garment to be selectively worn with the waist portion in shirred or unshirred condition, said means comprising a pair of spaced fastener elements secured to one of the web members and a pair of similarly arranged fastener elements secured to the other of said web members and adapted to cooperate with said first-named fastener elements, one fastener element of each pair being disposed at the ends of said web members.

4. In a garment of the character described, a pair of elastic web members disposed in a hem adjacent the waistline of said garment and each secured at one of its ends to said garment adjacent the front thereof, and means for fastening the other ends of said web members together in a pair of overlapping relations, in one of which the waist portion of the garment is shirred and in the other of which the waist portion of the garment is left unshirred, said means comprising a pair of spaced apart snap fastener elements secured to one of the web members adjacent its end with one of said snap fasteners located at the extreme end of said web and a pair of similarly arranged snap fastener elements secured to the other web member adjacent its end, said last-named fastener elements being complementary to said first-named elements.
